UNITED STATES PATENT OFFICE.

PAUL HEINZE, OF DETROIT, MICHIGAN.

LETTERING DEVICE.

Application filed August 7, 1926. Serial No. 127,738.

This invention relates to lettering devices and the object of the invention is to provide a lettering device by which the lettering may be accurately positioned on a drawing, map 5 or plat.

Another object of the invention is to provide a lettering device in which the lettering may be positioned relative to an angular, vertical or horizontal base line.

10 A further object of the invention is to provide a lettering device in which type is adapted to be mounted, the lettering device being so arranged that the user may determine the exact point on a drawing where 15 the lettering will appear.

Another object of the invention is to provide a lettering device so arranged that the type may be made to print above, below or exactly on a given line.

20 A further object of the invention is to provide a lettering device arranged to enable the operator to print figures or letters normal to a base line but divergent at any angle from such base line.

25 Another object of the invention is to provide a means for adjusting the device so that the plane of the type faces is absolutely parallel with the surface being printed.

These objects and the several novel features of the invention are hereinafter more 30 fully described and claimed and the preferred form of construction by which these objects are attained is shown in the accompanying drawings in which—

35 Fig. 1 is a plan view of a lettering device embodying my invention.

Fig. 2 is an end elevation taken from the right of Fig. 1.

40 Fig. 3 is a bottom view of the lettering device.

Fig. 4 is a front elevation thereof.

Fig. 5 is a section taken on line 5—5 of Fig. 1.

45 Fig. 6 is a section taken on line 6—6 of Fig. 2.

Fig. 7 is a section taken on line 7—7 of Fig. 1.

Fig. 8 is a section taken on line 8—8 of Fig. 1.

50 Fig. 9 is a section taken on line 9—9 of Fig. 1.

Fig. 10 is a section taken on line 10—10 of Fig. 4.

55 Fig. 11 is a section taken on line 11—11 of Fig. 1.

The device comprises a three sided frame

1 shown in Fig. 3 having four adjusting screws 2 in the four corners thereof. As shown in Fig. 2 the bracket 3 is formed integrally with the base 1 and is provided with a cylindrical upper end 4 through which a movable stem 5 extends as shown in Figs. 5 and 6. A pin 6 is secured in the cylindrical member 4 and extends through slots 7 provided therefor in the member 5. A coiled spring 8 is positioned in the member 5 and rests on the pin 6 and tends to hold the member 5 in the position shown in Figs. 5 and 6. The member 5 is provided with a knob 9 at the upper end by which the member 5 may be moved downwardly against the tension of the spring 8 by hand pressure. Secured to the lower end of the member 5 is a type holder 10 as shown in Figs. 1, 2, 3, 4 and 5. The type is mounted in this holder and is supported therein by the spacers 11 and a movable block 12 is provided at one end of the holder 10 which is adjusted by the screw 13 to put a pressure on the type and spacers to hold them in the casing. It will be noted from Fig. 2 that the type faces extend below the lower edge of the holder 10 and by pressing down on the knob 9 the type may be made to print. In order to hold the type holder 10 in proper parallel relation with the base at all times a pair of lugs 14 and 15 shown in Fig. 4 extend upwardly from the base and a set screw 16 is threaded through each lug as shown in Fig. 1 and engages the adjacent end of the holder 10. By this arrangement during vertical movement of the holder 10 up or down the holder is prevented from turning in the supporting bracket 4. As shown in Figs. 1, 3 and 4 an arm 17 is pivotally secured to each end of the frame 1 by means of a thumb nut 18. A second arm 19 is pivotally secured to the end of each arm 17 by a thumb nut 20 and the arms 19 are pointers which may be positioned to indicate the opposite ends of the type faces in the holder 10 as will be understood more particularly from Fig. 3.

In order to allow the operator to position the printing in relation to a given line, a zero line 21 is engraved on the under side of the base at each end thereof which is in alignment with the top of the type or the inner rear wall of the holder 10. A small screw shaft 22 is rotatably mounted at each end of the base which are each threaded through a nut 23 as shown in Fig. 3. Each nut 23, as will be understood from Figs. 8

and 9, is provided with a rib 24 riding in a groove 25 in the end of the base to prevent it from turning on the respective shaft 22. As shown in Fig. 3 a zero line 26 is engraved on the bottom of the nut 23 and on the upper face of the nut a central line 27 coincides with the zero line on the bottom of the nut as will be understood from Figs. 1 and 3. When it is desired to position the printing immediately below a given line the nuts 23 are set so that the zero lines 26 are in alignment with the zero lines 21 on the base, at which time by positioning the device on a plat or drawing the lines 27 on the top of the nuts are positioned in alignment with the given line on the plat whereupon by pressing down on the knob 9 the type may be made to print directly below the given line. In Fig. 3 the different lines below the zero line 21 are the center lines for different point type. For instance the first line below the line 21 represents the center line for eight point type, the second line is the center line for fourteen point type, the third line is the center line for eighteen point type and the bottom line is the center line for forty-two point type. The type shown in the holder is fourteen point type and in order to position this type centrally on a given line the shafts 22 are turned by means of the knurled ends until the zero lines 26 on the nuts correspond with the second line below the zero lines 21 on the base. By turning the device to the upright position shown in Fig. 1 the device may be set so that the central line 27 which is a continuation of the zero line on the bottom of the nut registers with the line on which the type is to be centrally positioned, at which time by pressing down on the knob 9 the type may be printed on the plat so that the given line is central of the type. As will be understood from Fig. 1 with the line 27 positioned on the center line of the fourteen point type the second line above the line 27 represents the top line of the fourteen point type while the second line below the line 27 represents the bottom line of the fourteen point type; thus at this time by positioning the second line below the line 27 on the two nuts 23 in registration with a given line the type will print above the given line. This device may be operated in the same manner for eight point, eighteen point and forty-two point type. In order to allow the lettering to be printed at a given angle to a base line an arcuate member 28 is provided having an arcuate slot 29 therein which is adapted to be positioned over the heads of the base adjusting screws 2 and a lock screw 31 is provided by which the arcuate member 28 may be clamped in any position. This member 28 as shown in Figs. 1, 2 and 4 is provided with an upturned lug 32 and a downturned lug 33. To

print with this arrangement a straight edge is laid along the base line and the device is positioned so that the downturned lug 33 and the corner 34 of the base engage the straight edge. At this time by pressing down on the knob 9 the lettering may be printed at any given angle to the base line depending upon the position in which the arcuate member 28 is set. This arcuate member may be removed and turned over and positioned in the same relation on the opposite end of the base or frame 1 at which time the lug 32 is the lower lug which engages the straight edge while the corner 35 of the base provides the opposite point of contact with the straight edge. By this arrangement the device may be set at any angle to a base line. The four screws 2 may be adjusted so that the surface of the type faces is absolutely parallel with the surface to be lettered. The type shown in the holder is preferably inked before each operation by means of a hand inking roller and the type may be readily changed by loosening the screw 13 to allow the letters or numbers to be replaced. With this device a drawing may be lettered uniformly without the irregularities usually produced by pen lettering and due to this regularity of the type a drawing lettered in this manner has a much better appearance than a hand lettered drawing or plat.

This device may be made to print on the circumference of a circle by turning the pointers outwardly and positioning the ends of the pointers on the center of the circle or if the circle is of too great a radius the pointers may be positioned on a radial line of the circle.

From the foregoing description it becomes evident that the device is very simple and efficient in operation, will not easily get out of order and provides a device which accomplishes the objects described.

Having thus fully described my invention, its utility and mode of operation, what I claim and desire to secure by Letters Patent of the United States is—

1. A lettering device comprising a base plate having an opening in the center, a vertically movable type holder movable toward the said opening, a support on the base plate for the type holder, a screw shaft at each end of the base plate, a nut on each screw shaft provided with graduations adapted to register with graduations provided thereon on the base plate, adjustable means for indicating the overall length of the printing faces of the type in the holder, and means for setting the device at any angle to a given line.

2. A lettering device comprising a base plate having an opening in the center, a vertically movable type holder movable toward the said opening, a support on the base

plate for the type holder, a screw shaft at each end of the base plate, a nut on each screw shaft provided with graduations adapted to register with graduations provided on the base plate, and adjustable means for indicating the overall length of the printing faces of the type in the holder.

3. A lettering device comprising a base plate having an opening in the center, a vertically movable type holder movable toward the said opening, a support on the base plate for the type holder, a screw shaft at each end of the base plate, and a nut on each screw shaft provided with graduations adapted to register with graduations provided on the bottom of the base plate.

4. A lettering device comprising a base plate having an opening in the center, a vertically movable type holder movable toward the said opening, yieldable means supporting the type holder on the base plate, adjustable means for indicating the position of the type relative to a given line, and adjustable means for indicating the overall length of the type printing faces.

5. A lettering device comprising a three sided base plate, a type holder, means supporting the type holder for vertical movement in relation to the base plate, guide means for holding the type holder in proper relation with the base plate, and adjustable indicating means for indicating the position of the type in the holder.

6. A lettering device comprising a three sided base plate, a series of adjusting screws 35 extending through the base plate, a type holder, means on the base plate supporting the type holder for vertical movement in relation to the base plate, and manually adjustable means for indicating the position 40 of the type in the holder.

7. A lettering device comprising a three sided base plate, a type holder, means on the base plate yieldably supporting the type holder for vertical movement in relation to the base plate, the type holder being adapted to be filled with type, and manually adjustable means for indicating the position of the type in the holder.

8. A lettering device comprising a base 50 plate having an opening in the center, a vertically movable type holder movable toward the said opening, a support on the base plate for the type holder and guide means preventing the type holder from turning in 55 relation to the base plate.

9. A lettering device comprising a base plate having an opening in the center, a vertically movable type holder movable toward the said opening, a support on the base plate for the type holder and adjustable 60 means for indicating the position of the type relative to a given line.

In testimony whereof, I sign this specification.

PAUL HEINZE.
